MOP AND METHOD OF MAKING SAME

Frederick A. Speik, South Pasadena, Calif.

Application March 21, 1935, Serial No. 12,188

9 Claims. (Cl. 300—21)

My invention relates to a mop and method of making the same.

In particular, my invention relates to a mop in which a longitudinal body of a swab consisting of cords arranged in parallel has one end firmly embraced in a metal sheath to form a head whereby the same may be quickly attached or removed from a corresponding socket at the end of a handle.

It has been difficult to devise a simple and economic construction to hold the strings of a swab firmly together so that they will not easily be pulled out and to compress the same into a small compass so that it may be conveniently attached and removed from a mop stick. It is an object of the present invention to provide a mop and a method of making the same whereby such a head may be quickly and efficiently provided. In particular, the construction contemplates the use of a pair of sheet metal plates between which the middle of the swab is placed, one of the sheet metal plates being wider than the other so that the lateral portions extending beyond the sides of the smaller plate may be clinched over the sides of the smaller plate after compressing tightly the end of the swab between the plates. Preferably, the interlocking of the two metal plates is strengthened by providing fingers of one plate and integral therewith to project through the cords of the swab and through corresponding slots in the other plate. The ends of the fingers projecting through the slots are then clinched over onto the plate. The metal plate thus interlocked and clinched together over the compressed portion of the swab is then cut in two transversely, thus forming two independent swabs or mops, each provided at one end with a metal encased head.

The object of forming a duplex mop in this manner and then cutting the same in two to form two independent mops is that difficulty is experienced when making the mops separately and encasing one end thereof by means of metal plates. It is essential for the proper compression of the ends of the mop within the metal plates that the cords lie in perfect alignment parallel to one another and this is easily accomplished when a mop of the double length is used for it is merely necessary to stretch the ends thereof in opposite directions, which automatically aligns the cords in parallel relation to one another.

With the above and other objects in view, which will appear as the description proceeds, my invention consists in the steps of the method of making a mop and the resulting product.

In the accompanying drawings, which form a part of the specification, I have illustrated the successive steps of the method and also the resulting product, and in which:

Fig. 1 is a plan view of a double length swab, 5 the middle portion between two metal plates.

Fig. 2 is a cross section on the line 2—2 of Fig. 1.

Fig. 3 is a view similar to Fig. 2 after the compressing operation and the clinching over of the 10 ends of the lateral portions of the wider plate as well as the fingers of the wider plate over the smaller plate.

Fig. 4 is a section on the line 4—4 of Fig. 2.

Fig. 5 is a section on the line 5—5 of Fig. 3. 15

Fig. 6 is a detailed view showing the plan after the pair of metal plates encasing the end of the swab has been cut in two.

Fig. 7 is a perspective view showing the assembly of the swab to a mop holder. 20

Figs. 8 to 13, inclusive, show a modified form in which Figs. 8 and 9 show a perspective view of the metal plates between which the swab is clamped as shown in the perspective view of Fig. 10. 25

Fig. 11 is a vertical section on the line 11—11 of Fig. 10.

Fig. 12 shows a perspective view of the assembled mop.

Fig. 13 is a cross section on the line 13—13 of 30 Fig. 12.

A swab made of a body of cords of a suitable material such as cotton, is arranged in a flat, rectangular body indicated at 10. The length of the same is double of that of a single swab for 35 the object is to cut the same in two equal parts to form two mops at the end of the operation. Preferably, the middle of the swab 10 is provided with a textile web 11 to hold the individual cords loosely together. The swab 10 is placed on a suitable support, such as a table, not shown, with its middle portion resting on a sheet metal plate 12 and the swab is stretched longitudinally, which causes the cords to align themselves in parallel. The metal plate 12 is somewhat wider 45 than the width of swab 10. Struck integrally from the plate 12 is a series of upstanding fingers 13, with their body portion parallel to the cords of the swab 10.

Another sheet metal plate 14 provided with 50 slots 15 of a number and position to correspond to fingers 13 of plate 12 is now placed on top of the swab 10 in alignment with plate 12. The top plate 14 is not as wide as plate 12 so that marginal portions indicated 12' of plate 12 project beyond 55

the sides of plate 12 and the sides of the swab 10, as shown in Figs. 1 and 2. By means of a power press or the like the plate 14 is now forced under great pressure downwardly toward plate 5 12, causing the body of cords of the swab 10 to be firmly compressed and the fingers 13 on plate 12 to project through slots 15 on plate 14. The fingers 13 as well as the marginal portion 12' of plate 12 are now clinched over plate 14, as 10 shown in Fig. 3, thus clamping and confining the cords of swab 10 within the metal plates 12 and 14. The metal plates and the swab confined therebetween are now cut transversely through the center, the metal plates having preferably 15 been weakened on the line of separation as indicated at 16, such as by scoring, to facilitate the cutting operation.

The head, which is indicated as a unity at 17, of the swab 10 and indicated in Fig. 6, may now 20 be placed in a corresponding metal socket 18 secured in the end of the mop stick 19 and held in position by means of a pair of set screws 20 passing through the socket 18.

In Figs. 8 to 13, inclusive, I have shown a modified construction of my mop in which 21 designates the lower plate having lateral portions 22 vertically extending therefrom. Vertical fingers 23 are stuck integrally from the plate 21 to form two pairs of parallel rows, the fingers in each 30 row being arranged in staggered relation and the plane of the body of the fingers being parallel to the cords of the body of the swab which is placed on plate 24. The top plate 24 is provided with a plurality of perforations or slots 25 arranged in pairs and so disposed that when plate 24 is placed over plate 21 fingers 23 will register with the perforations and when the plate 24, by suitable mechanism, is pressed down upon the swab 10 the upper ends of fingers 23 will project therethrough and may then be bent flush with the upper face of plate 24 with the extreme tips of said fingers entering and extending downwardly through the adjacent perforations 25', as clearly shown in Fig. 10. The upper end portions of vertical plates 22 are bent inwardly to lie flush on plate 24 in order to still further compress and clamp the cords in position within the two plates 21 and 24. A pair of channels 26 in top plate 24 and corresponding channels 27 in the bottom plate 21 are pressed inwardly, as shown in Figs. 10 and 11. Preferably, the channels 28 and 29 in the top plate 24 and bottom plate 21, respectively, are transverse to the channels 26 and 27. Rivets 30 passing from plate 24 to plate 55 21 may still further unite the metal plates in order to confine the swab securely. It should be remembered that considerable pressure is exerted by the swelling of the cords on the application of moisture, therefore, the clamping means should be made secure.

The metal plates and the swab confined therebetween are now cut transversely in the center indicated at 31, forming two swabs which may be removably locked in corresponding sockets at the end of a handle such as shown in Fig. 7, or a modified socket as shown on Figs. 12 and 13 may be used. Modified socket 32 is preferably made of hard rubber in which nuts 33 are embedded 70 for the reception of clamping bolts 34. The socket may be provided with a soft rubber bumper 35 in its upper face to prevent marring of the furniture when in use.

Various changes may be made in the steps of 75 the method and in the construction of the mop

by those skilled in the art without departing from the spirit of my invention as claimed.

I claim:

1. A method of making mops comprising placing a swab consisting of a body of cords in parallel alignment, clamping a pair of sheet metal plates having interlocking means about the middle of the swab, and cutting through the plates and the swab transversely to the axis thereof to form two separate mops. 5

2. A method of making mops comprising placing a swab consisting of a body of cords in parallel alignment, clamping a pair of sheet metal plates having interlocking means about the middle of the swab, and cutting through the middle of the plates and the swab transversely to the axis thereof to form two separate mops, one of the metal plates being provided with struck out fingers extending through corresponding slots in the other metal plate, and clinching the fingers over the 20 slotted plate. 15

3. A method of making mops comprising placing a swab consisting of a flat body of cords in parallel alignment, clamping a pair of sheet metal plates about the middle of the swab under power pressure, one of the metal plates extending laterally beyond the sides of the other plate, clinching the two plates together and cutting through the middles of the plates and the swab transversely to the axis thereof to form two separate mops. 25

4. A mop comprising a longitudinal swab having a flat body consisting of cords arranged in parallel, one end of the swab being tightly compressed and embraced by a pair of interlocked sheet metal plates forming a head, one of said plates being wider than the other and having its lateral portions clinched over the sides of the other plate, said wider plate being provided with fingers integral therewith and passing 35 through corresponding slots in the smaller plate, the ends of the fingers projecting through the slots being clinched over the face of the smaller plate. 40

5. A mop comprising a longitudinal swab having a body portion consisting of cords arranged in parallel, one end of the swab being tightly compressed and embraced by a pair of sheet metal plates forming a head, one of said plates being wider than the other and having its lateral portions clinched over the sides of the other plate, said wider plate being provided with fingers integral therewith and passing through 50 corresponding slots in the smaller plate, the ends of the fingers projecting through the slots being clinched over the face of the smaller plate, and rivets connecting the plates together. 55

6. A mop comprising a longitudinal swab having a body portion consisting of cords arranged in parallel, one end of the swab being tightly compressed and embraced by a pair of sheet metal plates forming a head, one of said plates being wider than the other and having its lateral portions clinched over the sides of the other plate, said wider plate being provided with 60 fingers integral therewith and passing through corresponding slots in the smaller plate, the ends of the fingers projecting through the slots being clinched over the face of the smaller plate, the plates being provided with outwardly extending 65 ribs. 70

7. A mop comprising a longitudinal swab having a body consisting of cords arranged in parallel, one end of the swab being tightly compressed and embraced by a pair of interlocked sheet 75

- metal plates forming a head, one of said plates being provided with fingers integral therewith, the other plate being provided with slots for the reception of the upper ends of said fingers, the 5 ends of said fingers projecting into slots being clinched over the face of the other plate and again downwardly through slots of the other plate into the body of the swab.
8. A mop comprising a longitudinal swab having a body consisting of cords arranged in parallel, one end of the swab being tightly compressed and embraced by a pair of sheet metal plates forming a head, one of said plates being wider than the other and having its lateral portions
- 10

clinched over the sides of the other plate, a fastening means integral with one of said plates and extending through the body of the swab and secured to the other plate.

9. A mop comprising a longitudinal swab having a flat body consisting of cords arranged in parallel, one end of the swab being tightly compressed and embraced by a pair of sheet metal plates forming a head, fingers integral with one plate and passing through the body of the swab 10 and having their upper ends secured to the other plate.
